**COMBINED BACKSPLASHER AND CONTROL
PANEL FOR ELECTRIC RANGES**

Edward W. Harrison and Arthur N. Beck, Jefferson
County, Ky., assignors to General Electric Company, a
corporation of New York

Application October 30, 1956, Serial No. 43,579

Term of patent 14 years

(Cl. D81—25)

FIG. 1

FIG. 3

FIG. 4

FIG. 5

FIG. 6

Fig. 1 is a fragmentary front elevation view of a range embodying a combined backsplasher and control panel for electric ranges, showing our new design.

Fig. 2 is a top plan view thereof.

Fig. 3 is a side elevation view thereof.

Fig. 4 is a sectional view taken along the line 4-4 in FIG. 1.

Fig. 5 is a sectional view taken along the line 5-5 in FIG. 1.

Fig. 6 is a sectional view taken along the line 6-6 in FIG. 1.

The dominant features of our design reside in the portions shown in full lines.

We claim:

The ornamental design for a combined backsplasher and control panel for electric ranges, substantially as shown and described.
